UNITED STATES PATENT OFFICE.

HARRY F. SMITH, OF LEXINGTON, OHIO.

PRODUCER-GAS APPARATUS.

No. 888,359

Specification of Letters Patent.

Patented May 19, 1908.

Application filed March 29, 1907. Serial No. 365,292.

To all whom it may concern:

Be it known that I, HARRY F. SMITH, a citizen of the United States, residing at Lexington, in the county of Richland and State 5 of Ohio, have invented certain new and useful Improvements in Producer-Gas Apparatus, of which the following is a specification.

My invention relates to improvements in what are known in this art as gas-producer 10 apparatus, more especially regulating devices therefor. Its objects are principally to provide for controlling the proportionate admixture of the steam and the air-blast as the same are delivered or fed to the ash-pit of 15 the producer; to advantageously use otherwise unfit liquids or water in effecting the aforesaid admixture; and to carry out the purposes of the invention in a simple, expeditious and effective manner.

20 Said invention consists of certain features or instrumentalities substantially as herein-after fully disclosed and specifically pointed out by the claims.

25 In gas producer apparatus for generating fuel-gas from carbonaceous fuels and particularly such as are designed to furnish gas for power-purposes it is of the utmost importance to control the proportion of steam or vapor carried along with the blast for delivery into the ash-pit of the producer.

30 My invention or apparatus is, as will be clearly disclosed later, intended to accomplish in a perfectly simple and automatic manner the aforesaid result and control the 35 saturated and heated air for that purpose, it being based upon the well known physical fact that for any given temperature air will hold in suspension in the form of vapor a certain definite proportion of water.

40 In the accompanying drawing illustrating the preferred embodiment of my invention—Figure 1 is a sectional elevation in part of the invention with parts broken away. Fig. 2 is a plan view of the same.

45 In carrying out my invention, I provide a suitable tank 1 preferably of sheet-metal, with a tightly closed bottom and a like top, which tank has, near its bottom, an air-inlet 2 and a waste-water outlet 3. Said air-inlet, in the 50 suction-type of producer, simply opens to the external atmosphere, but in the pressure-type of producer it has applied to it a suitable blower of any usual or preferred pattern.

Said tank has a short pipe or tubular extension 4 at its upper end; and opening outward laterally from which is a pipe 5 forming an air-outlet for said tank. A hot water-delivery pipe 6, leading from a suitable source of supply, enters centrally the upper end of the tank 1 for supplying hot water thereto, the 60 temperature of which water should be materially below the boiling point, preferably say one hundred and eighty degrees. This pipe is equipped with a suitable regulating valve 7 for controlling the water-supply there-through as presently fully disclosed, the same having a downward-extending stem 8 to the lower end of which is fixed a thermostat 10, at one end. The opposite end of said thermostat is fixed to and supported in position by a bracket-bar 11 suitably connected to the pipe 5. It will be noted that the valve-stem 8 depends through the upper end of the tubular extension or pipe 4 and has its lower end arranged therein, and that the 75 thermostat is disposed principally within the air outlet-pipe 5, with one end extending into the pipe 4, where it connects with the valve-stem, thus providing for exposing said thermostat to the action of any varying temperatures which may prevail within said outlet-pipe, as presently more fully made apparent.

The tank 1 is suitably filled in with numerous wooden slats or pieces 12, or other suitable material, laid crosswise or checker-work fashion, to form an extended superficial area therein, over which the water, when turned on at the valve 7 is caused to flow, the same finally leaving the tank via the waste-pipe 3. It will therefore be noted that 90 the air, admitted through the air-inlet 2 of the tank 1 by suction or pressure as the case may be, into the latter, will become suitably saturated with the hot-water and its temperature be raised as it is thus allowed or 95 caused to pass over the extended superficial area, resulting from the assemblage of wooden slats, and thus saturated be delivered out through the pipe 5 and finally into the ash-pit of the gas-producer, where, together with the steam or vapor thus generated, the same will be delivered to the producer.

In operation, it being assumed that the pipe 5 has been adjusted to deliver into the 105 ash-pit of a producer and the inlet-opening 2

is in communication with the external atmosphere, the action of the producer will draw cool air through said inlet and into the tank 1 and upward through the latter, and 5 into contact with, or over the filled-in wooden slats or pieces of other suitable material, the air being discharged through said pipe to the producer. Simultaneously a stream of hot water of about the temperature 10 before noted is discharged from the pipe 6 under the control of its valve 7 into the upper part of the tank 1. Said hot water 15 stream flows downward over said wooden slats, or other material used, wetting the latter and exposing a large area or surface of hot water to the incoming air. The water is in this way cooled, parting with its heat, and heating the air, the latter also being saturated with the moisture up to the limit of the 20 carrying capacity of its temperature at the time of discharge. This warm moisture laden air, in passing from the apparatus will come into contact with the thermostat 10. The latter is so adjusted as to close the valve 7 25 and accordingly cut off the hot-water supply when the temperature of the air exceeds a certain definite limit and to open the valve 7 when the temperature descends below said limit. It is apparent that it is thus made 30 possible to maintain in the outgoing air a uniform temperature and consequently a uniform per cent. of suspended moisture regardless of variations in the amount of air flowing. For it is plain that should the 35 temperature fall below the predetermined point, which it may be desired to maintain, the thermostat 10 will open the valve 7 and permit a much larger supply of hot water to the tank 1, whereby the temperature and moisture contents of the air supplied to the producer will be again brought to the standard condition. If on the other hand the temperature of the air and the consequent per cent. of suspended moisture should increase beyond 40 the desired limit, the thermostat would have the effect to immediately close the valve 7 thus cutting off the supply of water and allowing the temperature to again fall to the required point. In this way a uniform condition 45 of temperature and moisture of the outgoing air is maintained at all times and variations in the quantity of blast delivered are automatically provided for. The average amount of moisture carried in the air may be 50 readily regulated by accordingly adjusting the length of the valve-stem 8, thus providing for changing the temperature at which the valve 7 may be set for closing.

It is understood that any other convenient 60 form or make of thermostat may be employed herein in lieu of that shown. For ordinary producer gas work it is found that it is convenient to carry about one part by weight of moisture and nine parts by weight of air.

For this proportion it would be necessary to 65 carry a temperature for the outgoing air of approximately one hundred and thirty degrees Fahrenheit. Among the special advantages of this arrangement may be mentioned the fact that by its employment it is 70 possible to make use of waters for this purpose which are very impure, and which could not be used in a steam boiler for supplying steam in the ordinary way on account of the large amount of deleterious minerals held in 75 suspension.

With this apparatus it would be obviously possible to use sea-water or alkaline waters, since the amount of evaporation would not be sufficient to cause a precipitation of solid 80 matter; even in the event of some of the more solid matters precipitated no harm could result to the apparatus, and the deposited matter could be very readily removed.

I claim—

1. Apparatus of the character described, comprising means for receiving a regulated quantity of hot water for distribution through it, means for effecting a passage of air in the opposite direction through said hot 90 water receiving means, a thermostat arranged in a common outlet of said hot water receiving means for the escape and delivery of said air-currents thus saturated with moisture, and a valve for said hot water supplying 95 means controlled by the action of said thermostat.

2. Apparatus of the character described, comprising means for receiving a regulated quantity of hot water for distribution 100 through it, means for effecting a passage of air in the opposite direction through said hot water receiving means, a thermostat arranged in a common outlet of said hot water receiving means for the escape and delivery 105 of said air-currents thus saturated with moisture, a valve arranged in said hot water supplying means and a stem connected to said valve and to said thermostat, said hot water receiving means having an air-inlet for effecting the reverse passage through it of air-currents.

3. Apparatus of the character described, comprising means for receiving a regulated quantity of hot water for distribution 115 through it, a hot water supply pipe for said hot water receiving means, a valve arranged in said hot water supply pipe, and a thermostat arranged in a common outlet of said hot water receiving means and connected to said 120 valve for controlling the action of the latter, said hot water receiving means having an air-inlet for effecting a passage of air-currents in the opposite direction through said hot water receiving means.

4. Apparatus of the character described, comprising a tank, a valved hot water supply pipe therefor, a thermostat arranged in

a common outlet of said tank for the delivery therefrom of saturated air-currents, means effecting connection between the valve of said hot water supply pipe and said thermometer stat, said tank also having arranged therein means for distributing the passage of the hot water through it, and an air-inlet for effecting a passage therethrough of air-currents in

the opposite direction over said hot water distributing means, as set forth. 10

In testimony whereof I affix my signature, in presence of two witnesses.
